CLAIM

The ornamental design for a media desk, as shown and described.

DESCRIPTION

FIG. 1 is a front perspective view of the media desk of the present invention;

FIG. 2 is a front elevation view of the media desk of the present invention,

FIG. 3 is a rear elevation view of the media desk of the present invention,

FIG. 4 is a right side elevation view of the media desk of the present invention,

FIG. 5 is a left side elevation view of the media desk of the present invention,

FIG. 6 is a top plan view of the media desk of the present invention; and,

FIG. 7 is a bottom plan view of the media desk of the present invention.

Any features illustrated in broken lines do not comprise part of the presently claimed design.

1 Claim, 7 Drawing Sheets
